(57) **CLAIM**

The ornamental design for an electric salad spinner, as shown and described.

DESCRIPTION

FIG. 1 is a front elevational view of an electric salad spinner showing my new design;

FIG. 2 is a rear elevational view thereof;

FIG. 3 is a left side view thereof;

FIG. 4 is a right side view thereof;

FIG. 5 is a perspective view thereof; and,

FIG. 6 is an exploded perspective view thereof.

The broken lines illustrate portions of the electric salad spinner that do not form part of the claimed design.
